HENRY D. STOVER, OF NEW YORK, N. Y.

Letters Patent No. 83,671, dated November 3, 1868.

IMPROVEMENT IN MORTISING-AND-TENONING MACHINE.

The Schedule referred to in these Letters Patent and making part of the same.

Know all men by these presents:

That I, HENRY D. STOVER, of the city, county, and State of New York, have invented a new and useful Improvement in "Machines for Mortising and Tenoning Wood," whereby much time and labor are saved; and I do hereby declare the following to be a clear and exact description of the same, reference being had to the accompanying drawings, and letters of reference thereon, which form a part of my specification, and in which—

Figure 1, sheet 1, represents a side elevation of the combined machine for mortising and tenoning.

Figure 2, sheet 2, a plan, as seen in looking down upon said machine.

Figures 3 and 4, sheet 2, are views in detail of the method of working the "throw" of the mortising-tool.

Figures 5, 6, and 7, sheet 3, are views of the same machine where it is arranged for cutting gains in timber, as shown at Figure 8 of same sheet.

Like letters refer to like parts in each of the drawings. A and A' represent the foundation-bed of the machine, so constructed as to support both machines in such proximity to each other as that both may be driven from the same counter-shaft, as indicated by the red lines at B, fig. 1, sheet 1.

The most prominent feature of my invention relates to the method of graduating the "throw" of the mortising-tool, which is accomplished by means of two friction-disks, C and C', being operated alternately, as desired, by means of the rack d d', pinion D on shaft E, which is moved back and forth by the lever F, either by the hand or foot, said disks, by the movements of said pinion, being brought in contact with the perimeter of a friction-wheel, g, which has upon its axle a bevel-pinion, that operates the screw h, which works through the slide d, that carries the crank-pin m, as best seen at fig. 3, sheet 2.

By operating the pinion D, which engages in the racks d and d', the two disks, C and C', are brought in contact with the outer or inner surfaces of the wheel g, which will turn the screw h so rapidly that the crank-pin m is driven almost instantly either to or from the centre, as desired, thus graduating the throw of the tool T, as desired.

Another prominent feature of my invention consists in so arranging the cutter-heads for tenoning-machines, as that they can be moved to and from the timber to be worked; and also, by the introduction of a third cutter, at a right angle to the other two, a double tenon may be formed, as shown at z, sheet 1.

Again, I can readily so adjust the cutter-heads, either by removing one or more of them, as shown at fig. 7, sheet 3, as that the machine will be well adapted for cutting or forming "gains" or notches in timber, as shown at fig. 8, sheet 3.

Based upon the idea that every mortise requires a tenon, I have combined the machines for performing these two operations, on one and the same bed, thereby

saving much space in the shop, and permitting the same operatives to attend both machines.

Having premised, in a very general manner, some of the leading points in this invention, I will now proceed to describe the parts in detail, whereof

A and A' represent, as already remarked, the bed or frame for both machines.

B, the driving-shaft, which communicates motion to both, by the direct and quarter belts, as indicated in fig. 1, sheet 1.

H is the frame or bed that supports the timber to be mortised, and it is supported upon and is capable of being raised or lowered, by the two screws s s, to which motion is given by the bevel-wheels on shaft t.

These two screws being driven by the one shaft will carry the bed either upwards or downwards in a perfectly parallel or level position.

The bed H is also capable of being moved inward or outwards from the machine, as desired.

K is the support and guide for carrying the tool T, said tool being operated by a pitman, P, the lower end of which is connected with the crank-pin m, in the sliding stock d, which is driven to or from the centre, as already described, for the purpose of increasing or diminishing the "throw" or motion of the tool T.

Many devices have been planned for graduating the throw of the tool or chisel in mortising-machines, but I am convinced that this is the most complete and durable of any device as yet given to the public, and it is also so easily operated, that the workmen using such machines prefer it to all other devices.

The tenoning-attachments are mounted upon the sliding bed L, which works in a rebate in the combined bed-plate A and A', best shown at L, fig. 6, sheet 3.

Upon the inner end of said bed L, in suitable bearings, is the driving-shaft S, which gives motion to the cutters by means of belts, indicated by the red lines in fig. 1, sheet 1.

The cutter-heads are of the ordinary form, but mounted at the extremity of two arms, whose opposite ends are attached around the driving-shaft S, thereby holding said cutters at all times, the same distance from the driving-pulley.

These arms are adjusted and held to any position, by means of the binding-screws and slotted stud, as shown at p p, figs. 1 and 7.

This arrangement permits the adjustment of the cutters to any space desired for the various sizes of tenons, and, as so arranged, will form the single tenon, as shown at z, sheet 1.

But, upon the same bed L, and upon an adjustable bracket at z, I have introduced another cutter-head, in such relation to the other two, as that, by simply sliding the bed L further forward, after the first two cutters have done their work, a double tenon will be formed, as shown at z', sheet 1.

By the same machine also, when arranged as shown at fig. 7, sheet 3, where only one of the cutter-heads is retained in working-position, I am enabled to form "gains" or notches, as shown at fig. 8 of sheet 3.

This is a most admirable advantage in the framing of heavy timbers, as in car and bridge-building, and from the fact that it is much easier to adjust the cutters to the work, than to shift such large masses to and from the machines, as is now done in all other machines with which I am acquainted.

I do not claim the method of cutting one or more tenons, by means of circular rows, as that has been done by C. P. S. Wardwell, and is shown in his patent, No. 11,625, of August 29, 1854; but

What I do claim, and desire to secure by Letters Patent, is—

1. The bed-plate A and A', when so constructed

that the cutter-heads may be worked back and forth, or to and from the work, substantially as described.

2. Varying the throw or motion of the chisel in mortising-machines, by means of the friction-disks C and C', when arranged substantially as described.

3. The cutter-heads, attached to levers N and N', in combination with cutter-head x, when constructed and arranged as described, for the purpose set forth.

4. Mounting a cutter-head upon the adjustable lever N, attached to the sliding bed L, so that gains or notches may be readily formed in heavy timbers, substantially as described, and for the purpose set forth.

H. D. STOVER.
